UNITED STATES PATENT OFFICE.

JAMES J. ROBY, OF CLEVELAND, OHIO.

MINE-CAR.

1,087,318.

Specification of Letters Patent. Patented Feb. 17, 1914.

Application filed November 15, 1912. Serial No. 731,479.

To all whom it may concern:

Be it known that I, JAMES J. ROBY, citizen of the United States, residing at Cleveland, in the county of Cuyahoga and State 5 of Ohio, have invented certain new and useful Improvements in Mine-Cars, of which the following is a specification.

This invention has reference to improvements in mine cars, and the invention consists in the construction of the car and the parts and combinations thereof substantially as shown and described and particularly pointed out in the claims.

In the accompanying drawings Figure 1 is a plan view of my new and improved car horizontally sectioned at one of its wheel bearings. Fig. 2, Sheet 2, is a side elevation of the car and Fig. 3 is a longitudinal sectional elevation thereof through the center lengthwise. Fig. 4 is a cross section of the truck on the line of one of the wheel axles, and Fig. 5 is an end elevation of the truck or truck frame alone. Fig. 6 is a cross section of the truck on the irregular line 6—6, Fig. 1, showing an elevation of the lubricating means for the wheels. Fig. 7, Sheet 1, is a side elevation of the lower portion of the car body. Fig. 8 is a sectional elevation of one of the car wheels with bushing fixed 30 therein, and Fig. 9 is a perspective view of the bearing sleeve proper for said wheel. Fig. 10 is a perspective view of one of the axle bearing blocks. Fig. 11 is a cross section on line x—x, Fig. 12, and Fig. 12 is a longitudinal section of the lubricating force pump. Fig. 13 is a cross section on line y—y, Fig. 12.

The car as thus shown comprises several important improvements upon mine cars as heretofore known and made and which include, among other things, a body b which is essentially distinct and separate from the truck and removably seated thereon and divested of the draft means which heretofore 45 have been directly connected with the bottom of the car body.

Heretofore as mine cars have been built there was no distinct truck as such and the car axles and buffers were supported directly from the bottom of the body or frame of the car, so that the construction of mine cars with separate and independent bodies and trucks is a new departure in the art in so far as it is familiar to me. In this 55 change of construction I have sought to relieve the body of the car from the injurious

effects of impact when the cars are run in heavy trains as is now the practice and to construct a truck which would take such impact without injury. In modern car service 60 it is the practice to operate the cars by electrical or other power in trains of many cars each, say fifty to seventy-five in a train, and the tracks are liable to have sharp curves and steep grades which are exceedingly trying to the cars with the incident jamming they receive. Hence the desirableness of relieving the car body of these effects in transit and having a truck which can withstand all shocks without injury. Hence the car 70 body is made a wholly independent part and is seated here and there upon the truck and provided with stop lugs 2 or their equivalent at its bottom which engage suitable cross portions 3 on the truck and prevent sliding of the body on the truck, the said cross portions in this instance being preferably the edges of the heavy top plate 75 14 constituting a portion of the truck frame. I may or may not employ removable bolts 80 front and rear through the holes 4 to further secure the body of the truck, but in any event the said body has no direct connection with the draft rigging or means for coupling the cars together and is a separate member 85 as already described.

The truck itself is especially designed to meet the requirements of a car which is operated in a long and heavy train as described. To these ends I build the same with 90 comparatively heavy I beams 5 at the middle thereof lengthwise where the strain is greatest and which run the full length of the truck and are positioned side by side in such relation as to leave room between for 95 the draft rigging. The said rigging comprises the draft bars 6 at the ends of the car and which also serve as bumpers to cushion the impact, and each bar has a coupling head h outside and a shank inside 100 wound with a heavy spiral spring s which is suitably buttressed by a collar 7, or its equivalent, fixed between the said I beams 5. The said truck frame is further constructed with a channel iron bar 8 full length on each side, Fig. 5, and suitable cross bars or plates 10 here and there and longitudinal trusses 11 and transverse trusses 12, as seen in Figs. 2 and 5, respectively, the whole being firmly bolted together and constituting a frame 110 110 that is invincible as against shock and strain delivered against its ends. In addition,

however, and as a further precaution against racking the truck injuriously I bolt heavy plates, 14 and 15, top and bottom respectively over the middle portion of the truck and of a width to overlap the car axles α . These plates supplement the truck across both axles where the strain on the truck is greatest and make the frame doubly rigid and durable in this portion.

- 10 Now, having a truck frame constructed substantially as thus described, with draft rigging at both ends arranged between the middle beams thereof, it will be noticed that the head portion h of the draft-bar is flanked on each side by an impact or shock absorbing wing or member 18 adapted to receive side thrusts on the car in short bends or turns in the road. To this end the said side wings or members 18 are pivoted at 19
 15 at the base of head h and have slotted outer portions adapted to slide within limits in the sides and ends of the truck on pins 20, Fig. 1. The central head h is thus supplemented by the said side heads or wings 25 18, and their function is common and mutual with head h in so far as serving as buffers for the car against shock from the train is concerned, especially if the effect be direct or at an angle to the direct line of 30 travel.

Further invention herein resides in the construction of the bearings for the carrying wheels w and in the means for lubricating the same. Thus, the axles α , which sustain the usual relation to the truck near its middle portion are supported in bearings or bearing blocks d fixed firmly in the truck frame and provided each with a central transverse bore for the axle and an open slot 40 21, Fig. 10, horizontally in the outer side to receive the wings or projections 22 on the bearing sleeve c , Fig. 9, and which wings are bolted firmly in said blocks d , but with the understanding that the said sleeve can 45 be removed and inverted when it becomes excessively worn. It is well known that the tendency is to wear the lower portion of the bearing to a more or less flattened shape, and I provide a removable and reversible 50 bearing upon the axle α to take this wear and save the axle, as it is cheaper and easier to reverse the sleeve or to provide a new one than it is to provide a new axle. The said bearing sleeve c is thus made essentially the immediate bearing member for the wheel and a removable bushing f is fixed in the hub of wheel w and rides over the said bearing sleeve as in Fig. 6. The lubricating oil or grease enters between these 55 parts through bore holes h' endwise in the wings 22 and the coincident slots g in the sleeve or bearing c . Two sets of bores h' and slots g are shown in each bearing which provide for reversing the said 60 bearings when they become unduly worn
 65

at the bottom as described. Only the inner bore and corresponding slot are used at any time and an oil or grease supply tube n is connected therewith and extends back to the force feed pump m by which the lubricant is supplied to the said tubes n , one for each wheel. The said lubricating means are not designed to operate constantly but rather intermittently and at pre-determined intervals and times, and the lubricant preferably is not a free running oil but rather of the consistency of grease and which will feed under suitably applied pressure and only then, thus economizing the amount used and applying only a predetermined quantity, more or less, at a given time. To these ends the pump cylinder m has suitable nipples 24 on its head 25 to engage the lubricating tubes n upon and a piston 26 is mounted on a screw rod 27 and is fed forward a limited distance by every partial rotation of the said rod, the said piston being splined or otherwise held to a direct sliding movement back and forth in the cylinder. The shank of the said screw is squared at its end 29 to engage a tool thereon to turn said screw and carries a lever 28 which serves to rotate the said screw a fraction of a complete circle at a time according to the means provided to effect such rotation, as for example a fixed stop P at the end of a trip positioned at the side of the track to engage the said lever and cause it to turn a given distance before it becomes automatically released from the stop and is slowly restored by the spring 30. The said lever is free to return on the screw shank without rotating the screw and engagement therewith is effected by a pawl 31 pivoted on the head 29' of said lever which engages a ratchet disk 32 fixed on shaft 27 and causes the rotation of said shaft when the lever 28 is turned forward as above described. Thus a very slight forward feed movement can be imparted to the piston 26 and the pressure induced thereby will force-feed the desired amount of lubricant to all the wheel bearings at the same time as described. It will be observed that lever 28 has a side flange 31 upon which the said stop, not shown, engages and from which it escapes when the desired movement of said lever has been obtained.

Obviously, there will come a time when the piston 26 will reach the end of its travel on screw 27 and when further feed of lubricant cannot occur, and this is determined by the engagement of the piston with the nut or collar 33 on the said screw. One effect of this engagement is to lock the screw and piston together into resistance against retracting spring 30, and when the lever 28 remains inclined and does not return it tells that the piston has exhausted its feed movement and needs restoration. Such restora- 130

tion is effected by applying a wrench or other tool to the pawl 31' to disengage it from the ratchet disk 32 and also to shank 29 of the screw 27 and reversing rotation 5 until the piston is carried back to starting position. When this has been done and the pump is to be re-supplied with the lubricant the supply is effected through the pipe 35, Fig. 1, which discharges into the end of the cylinder *m* and with which any suitable force feed device can be connected after removing the screw cap 36.

What I claim is:

1. In mine cars, a truck constructed with a pair of I beams lengthwise at its middle to receive the direct thrust upon the car and channel bars at its sides, and cross connections and truss braces combining said beams and bars in a unitary rigid structure.
2. In mine cars, a truck having a pair of I beams centrally its entire length and draft rigging slidably mounted within limits between said beams, and springs in said rigging to cushion the impact between cars.
3. A mine car having a truck with I beams lengthwise through its center and spring pressed draw-bars between said beams at its ends adapted also to serve as buffers, said bars having draw-heads and side wings pivoted on said heads and slidably mounted in their outer portion on said truck and adapted to relieve impact at an angle to the direct line of travel.
4. A mine car having a truck with sheet metal plates fixed across its middle portion top and bottom, in combination with a car body having downward projections engaging the edges of the upper of the said plates to prevent sliding of the body on the truck.
5. A mine car having an all metal truck constructed with I beams lengthwise at its middle and channel bars at its sides, cross braces connecting said beams and bars and plates connected or riveted across the top and the bottom of the truck in its middle section and overlapping the car axles, and truss braces lengthwise and transversely of said truck.
6. A mine car having a truck with fixed bearing blocks for the car axles and invertible bearing sleeves over the axles and provided with projections bolted in said blocks.
7. A mine truck having wheel supporting axles fixed therein and wheel bearings sleeved over said axles and rigidly locked

against rotation, and said sleeves provided with channels lengthwise in the walls thereof to supply a lubricant thereto.

8. A truck for mine cars having fixed 60 wheel supporting axles, bearing sleeves for the wheels over the ends of said axles having projections on their inner portions through which said sleeves are fixed in place and said sleeves having lubricating channels with entrance through said projections.

9. A mine car comprising a car body and a separate truck therefor having beams, shafts extending transversely through said beams, wheels on said shafts, and draft appliances mounted at the ends of said beams.

10. A mine car comprising a truck and a body removably secured thereon, said truck having draft appliances at either end and longitudinal beams and bars at its center and sides, and wheel axles transversely through the central beams on the draft line.

11. A mine car comprising a car body and a separate truck for said body comprising beams therefor longitudinally the full 80 length and center of the truck, longitudinal side bars, axles extending transversely through said central beams, bearing blocks on the side bars, and wheels for said shafts.

12. A mine car having means to lubricate 85 the carrying wheels thereon comprising a force pump provided with a fixed cylinder and a direct acting piston, a screw rod engaged through said piston and a lever and ratchet mechanism to rotate said screw rod 90 and actuate said piston.

13. A mine car and a force feed pump for a lubricant mounted thereon having a piston splined to travel directly and a feed screw to actuate said piston having an exposed end adapted to engage a tool thereon to rotate said screw and return the piston to starting position.

14. A mine car having a pump to supply a lubricant thereto provided with a cylinder, a piston splined therein and a screw on which said piston is mounted, in combination with a supply pipe for the lubricant adapted to discharge into the inner end of said cylinder.

In testimony whereof I affix my signature in presence of two witnesses.

JAMES J. ROBY.
